UNITED STATES PATENT OFFICE.

WILLIAM BARTHOLOMEW AND CHARLES H. ALLEN, OF CHICAGO, ILLINOIS, ASSIGNEES
TO TROY LAUNDRY MACHINERY COMPANY, LTD., OF CHICAGO, ILLINOIS, A CORPO-
RATION OF NEW YORK.

ELECTRICALLY-OPERATED CENTRIFUGAL EXTRACTOR.

1,203,567.

Specification of Letters Patent.

Patented Nov. 7, 1916.

Application filed February 20, 1913. Serial No. 749,604.

To all whom it may concern:

Be it known that we, WILLIAM BARTHOLOMEW and CHARLES H. ALLEN, citizens of the United States, residing at Chicago, in the 5 county of Cook and State of Illinois, have invented certain new and useful Improvements in Electrically-Operated Centrifugal Extractors, of which the following is a specification.

10 Our invention relates in general to centrifugal extractors, and more particularly to electrically operated extractors.

The high speed at which the baskets of centrifugal extractors are rotated renders 15 their use dangerous to careless operators unless such extractors are provided with safety appliances for preventing access to the baskets while they are rotating. In order that such safety devices may fully protect the 20 operators, it is necessary that access should be prevented to the baskets, not only while the power is applied to rotate them, but after the disconnection of the driving power and while the baskets continue to rotate by 25 momentum at dangerous speeds.

The primary object of our invention is to provide a centrifugal extractor with an electrically actuated lock for the cover, which will continue in locked position as long as 30 the basket continues to rotate.

A further object of our invention is to provide an electrically operated centrifugal extractor, or similar machine, in which the usual safety cover must be closed before the 35 motor can start and must remain closed while the motor continues to rotate, and in which the cover cannot be opened while the machine continues to rotate, even after the current has been cut off from the motor.

40 A still further object of our invention is to provide an electrically driven centrifugal extractor with an electrically actuated lock for the cover, the driving motor and the lock being so connected that the motor cannot 45 start until the lock has been actuated to retain the cover closed, and the lock cannot be removed to unlocked position while the extractor continues in operation.

A still further object of our invention is 50 to provide an electrically driven centrifugal extractor, or similar machine, with an electrically actuated lock for the safety cover, which will effectively prevent injury to the

operators, and which will be simple in construction and efficient in use. 55

Our invention will be more fully disclosed hereinafter with reference to the accompanying drawings, in which the same is illustrated as embodied in a convenient and practical form, and in which—

Figure 1 is a rear elevational view; Fig. 2, a side elevational view with parts broken away; Fig. 3, a diagram showing electric circuits for actuating the motor and lock; Fig. 4, an enlarged cross sectional detail 65 on line 4, Fig. 2; Fig. 5, an enlarged detail of the centrifugally operated controller for the lock; and Fig. 6, an enlarged detail of the motor controller actuated by the lock. 60

The same reference characters are used to 70 designate the same parts in the several figures of the drawings.

Reference character A designates the casing of a centrifugal extractor within which is inclosed the rotary basket a. 75

B designates a support for the casing which is provided with a base b adapted to be secured to a floor, or other underlying surface.

D designates the basket spindle upon the 80 upper end of which the basket is supported and by which it is rotated.

d designates a pulley fixed to the spindle D and engaged by a driving belt E.

C designates a cover pivotally secured at 85 its rear edge to the usual water ring A' around the top of the opening A, while a' designates the water guard projecting upwardly from the rear of the water ring.

F designates an electric motor provided 90 with a pulley f around which extends the driving belt E, so that the motor is thereby operatively connected with the spindle to rotate the basket.

G designates any suitable support for the 95 motor F, which may be conveniently secured to the support B of the casing by means of flanges such as shown at g in Fig. 2.

A plurality of weights H are pivotally secured by links h to the spindle D in any suitable manner, as by means of a ring H' surrounding and clamped to the spindle by clamp screw h'.

K designates a disk loosely surrounding 105 the spindle D formed of any suitable insulating material and carrying on its upper

- surface a contact annular plate K' formed of any suitable conducting material. The disk K is pivotally connected to the several weights H by means of links k. L' and L² indicate brush holders which are secured to and suitably insulated from the legs of the supporting base B of the casing. The brush holders carry at their inner ends brushes l' and l² which overlie the conductor ring K'.
 5 M designates a solenoid supported adjacent the rear of the casing A as by means of a bracket m secured to the casing and provided with vertical side members m', m² which support at their lower ends a rest m³ for the lower end of the core N of the solenoid when the latter is deenergized.
 o designates a bolt pivotally connected to a bracket O secured upon the cover C at the rear thereof but eccentrically with respect to its hinge c. The bolt o extends through an opening o' in the water-guard a' and has a path of movement when the cover is opened intersecting the path of movement of the core N of the solenoid M. Secured 20 to the lower end of the core N is a disk P formed of any suitable insulating material upon which is supported an annular conducting ring P'. R' and R² designate brush-holders which are supported by and suitably insulated from the side members m' and m² of the bracket which supports the solenoid.
 r' and r² indicate brushes carried by the brush-holders R', R², respectively, and overlying the conductor ring P', as shown in Fig. 6.
 S designates a switchboard supported in any suitable manner, as by means of brackets s, mounted at their lower ends on the base G upon which the motor F is mounted.
 40 S' designates a motor starter of any suitable construction, which need not be described in detail, inasmuch as it forms no part of our invention.
 45 T indicates the main switch which is mounted upon the switchboard S.
 The leads forming the circuits of the motor and solenoid will be pointed out in connection with the following description of the operation and with particular reference to the diagram shown in Fig. 3. When the switch T is open and the basket is not rotating, the solenoid is not energized, and hence the core N thereof falls by gravity 50 and rests at its lower end upon the stop m³. This position of the core removes the conductor ring P' from contact with the brushes r' and r². The spindle D not being in rotation, the weights H fall by gravity toward the spindle and thereby permit the disk K and with it the conductor ring K' to drop away from the brushes l' and l². This position of the core N removes its upper end from the path of the bolt o so that the cover C may be raised to place within the basket

the articles from which it is desired to extract moisture. After the articles have been placed in the basket, the cover is closed which withdraws the bolt o from the path of the core N.

In order to rotate the basket the main switch T is closed which completes the following circuit: lead t extending from a source of electricity, through the adjacent member of the switch T, to lead t', through the series and shunt windings F' and F² of the field of the motor, from the shunt winding F², through lead f² to the starter S', and thence through the lead t⁵ and adjacent member of the main switch T to the return lead t⁶. The circuit from the series winding F' of the field extends through the armature F³, through the lead t², through the auxiliary winding M' of the solenoid, through the lead t⁴ to the starter S, and thence through the lead t⁵ and switch T to the return lead t⁶.

The circuit above described energizes the solenoid M so that the core N is lifted to the position shown in full lines in Fig. 2, 90 in which it extends across the path of movement of the bolt o, thereby preventing the lifting of the cover C. In the circuit above described, the auxiliary winding M' of the solenoid constitutes a sufficient resistance in 95 the armature circuit to prevent the operation of the motor, but immediately upon the core of the solenoid being elevated, the conductor ring P' engages the brushes r' and r², thereby short circuiting the auxiliary winding M' of the solenoid and closing the armature circuit from the lead t², through the lead t⁷, to brush r², through conductor ring P', to brush r', to lead t⁸, to the lead t⁴, and thence through the starter and switch to the return lead t⁶. The resistance afforded by the auxiliary winding M' of the solenoid being thus cut out of the armature circuit, the motor is operated and through the motor pulley f, belt E, and pulley d imparts rotary movement to the spindle D and with it the basket a. The rotation of the spindle D causes the weights H to be thrown outwardly by centrifugal force, thereby raising the disk K and bringing the conductor ring K' into contact with the brushes l' and l². The following circuit is thereby closed through the main winding M² of the solenoid: lead t, lead u, brush l², conductor plate K', brush l', lead u', main winding M² of the solenoid, lead u², back to the return lead t⁶. This circuit energizes the solenoid so as to retain the core in its elevated position to obstruct the movement of the bolt o, and hence prevent the raising of the cover C. It will be observed that this circuit, through the main winding of the solenoid, does not include the main switch T, and hence after the switch T has been opened to discontinue the motor circuit, the circuit will 130

still continue through the main winding of the solenoid as long as the spindle D rotates. The cover of the basket will therefore be locked in closed position until the basket has discontinued to rotate and the weights H have assumed vertical positions, and thereby broken the circuit through the conductor ring K' and brushes l' and l².

From the foregoing description it will be observed that by our improvements the motor cannot be started until the cover is closed, inasmuch as the position of the bolt o above the core N will prevent the latter being lifted, and hence prevent the closing 15 of the armature circuit around the resistance afforded by the auxiliary winding M² of the solenoid. It will therefore be evident that even though the switch T is closed the motor will not start until the cover has been 20 closed. It will be further observed that after the cover has been closed and rotary movement imparted to the basket through the motor, the cover cannot be raised while the basket continues to rotate even after the 25 motor circuit has been broken. It will therefore be seen that we have invented an electrically actuated lock for the cover of centrifugal extractors which will insure the cover being closed at all times during the 30 rotation of the basket, and that more specifically we have invented an electrically driven centrifugal extractor provided with an electrically actuated lock for the cover in which the motor cannot be started until the cover is 35 closed, and in which the cover cannot be opened as long as the basket continues to revolve.

While we have illustrated and described our invention as embodied in a centrifugal 40 extractor and have defined the same in the following claims with reference to such embodiment thereof, yet we do not wish thereby to be understood as restricting the application of our invention to centrifugal extractors, but intend thereby to protect it for whatever uses it may be adapted and in whatever forms it may be capable of practical embodiment.

What we claim is:

- 50 1. In a centrifugal extractor, the combination with a rotating member, of a safety guard for protecting said member, an electrical motor for rotating said member, and electrically actuated means for automatically locking said guard in closed position during the rotation of said member, said means being operative independently of the electromotive force generated by the motor acting as a generator.
- 60 2. In a centrifugal extractor, the combination with a rotating member, of a safety guard for protecting said member, electrically actuated means for locking said guard in closed position, and a circuit for said 65 electrically actuated means independent of

the armature circuit and comprising a controller automatically operated by said rotating element.

3. In a centrifugal extractor, the combination with a rotating member, of a safety 70 guard for protecting said member, electrically actuated means for locking said guard in closed position, and centrifugal means operated by the rotation of said member for automatically controlling the circuit of said 75 electrically actuated means.

4. In a centrifugal extractor, the combination with a rotating member, of a safety guard for protecting said member, a bolt 80 connected with said guard and reciprocated by the opening and closing thereof, an electromagnet, a sliding plunger actuated by said electromagnet and having a path of movement intersecting that of said bolt, and means actuated by said rotating member for 85 controlling the circuit of said electromagnet, whereby during the operation of said member said plunger will obstruct the movement of said bolt necessary to permit the opening 90 of said guard.

5. In a centrifugal extractor, the combination with a rotating basket, of a cover for said basket, means for rotating said basket, electrically actuated means for locking said cover in closed position, and centrifugal 95 means operated by the rotation of said basket for automatically controlling the circuit of said electrically actuated means.

6. In a centrifugal extractor, the combination with a basket, of a cover for said basket, means for rotating said basket, a bolt connected with said cover and reciprocated by the opening and closing thereof, an electromagnet, a plunger actuated by said electromagnet and having a path of movement intersecting that of said bolt, and centrifugal means operated by the rotation of said basket for controlling the circuit of said electromagnet, whereby during the rotation of said basket said plunger will obstruct the 100 movement of said bolt necessary to permit the opening of said cover.

7. In a centrifugal extractor, the combination with a rotating member, of a safety 115 guard for protecting said member, an electric motor for rotating said member, a manually operative switch for controlling the circuit of said motor, and means controlled by said safety guard for preventing the operation of said motor when said safety 120 guard is in open position, said means being arranged to automatically permit the operation of said motor when said guard is closed, after an attempt has been made to start the motor with said guard in open position.

8. In a centrifugal extractor, the combination with a rotating member, of a safety guard for protecting said member, an electric motor for rotating said member, a 130

manually operative switch for controlling the circuit of said motor, a lock for retaining said safety guard in closed position, and means controlled by said lock for permitting the operation of said motor only when said safety guard is locked in fully closed position.

9. In a centrifugal extractor, the combination with a rotating member, of a safety 10 guard for protecting said member, an electric motor for rotating said member, a manually operative switch for controlling the circuit of said motor, a lock for retaining said safety guard in closed position, a resistance in the circuit of said motor for preventing the operation thereof, means for automatically cutting out said resistance, and means for preventing the cutting out of 15 said resistance while said safety guard is in 20 open position.

10. In a centrifugal extractor, the combination with a rotary basket, of a cover for said basket, an electric motor for driving said basket, electrically operated locking 25 mechanism for locking said cover closed, a switch actuated by said locking mechanism for controlling the operation of said motor, and a controller mechanically operated by the rotation of said basket for maintaining 30 said locking mechanism in position to lock the cover closed during the rotation of said basket.

11. In a centrifugal extractor, the combination with a rotary basket, of a cover 35 for said basket, an electric motor for driving said basket, an electromagnet having main and auxiliary windings, means for initially closing a circuit through said motor and the auxiliary winding of said magnet, and the auxiliary winding constituting a sufficient 40 resistance to prevent the operation of said motor, an armature actuated by said magnet, a switch actuated by said armature when said magnet is initially energized for 45 short circuiting said auxiliary winding of the magnet, a controller actuated by the rotation of said basket for closing a circuit through the main winding of said magnet, and interfering connections between said 50 armature and cover for preventing the movement of said armature necessary to actuate said switch when said cover is open and for preventing the opening of said cover when said magnet is energized.

55 12. In a centrifugal extractor, the combination with a rotary basket, of a cover for said basket, a spindle upon which said basket is mounted and by which it is rotated, a motor for driving said spindle, a 60 solenoid having main and auxiliary windings, means for initially closing a circuit

through said motor and the auxiliary winding of said solenoid, said auxiliary winding constituting a sufficient resistance to prevent the operation of said motor, a 65 plunger in said solenoid, a switch actuated by said plunger when the solenoid is initially energized for short circuiting said auxiliary winding of the solenoid, a centrifugal controller operated by the rotation 70 of said spindle for closing a circuit through the main winding of said solenoid, and interfering connections between said plunger and cover for preventing the movement of said plunger necessary to actuate said switch 75 when the cover is opened and for preventing the opening of said cover while said solenoid is energized.

13. In a centrifugal extractor, the combination with a rotating member of a safety 80 guard for protecting said member, an electric circuit for controlling the operation of said rotating member, a resistance coil in said circuit to prevent operation of said rotating member when said circuit is closed 85 with said guard in open position, and means actuated by said resistance coil to cut said coil out of said circuit and permit operation of said rotating member when said guard is closed. 90

14. In a centrifugal extractor, the combination with a rotating member of a safety 95 guard for protecting said member, a motor for rotating said member, an electric circuit for controlling said motor, a switch for connecting said circuit with a supply circuit, and means actuated by said supply circuit independently of said switch for preventing movement of said guard during the continued rotation of said member after 100 said switch has been opened.

15. In a centrifugal extractor, the combination with a rotating member of a safety 105 guard for protecting said member, an electric circuit for controlling said motor, a switch for connecting said circuit with a supply circuit, means for preventing the operation of said motor when the switch is closed with said guard in open position, and means actuated by said supply circuit independently of said switch for preventing movement of said guard during the continued rotation of said member after said switch has been opened. 110

In testimony whereof, we have subscribed 115 our names.
